DESIGN FOR A THERMOMETER CASE

Harry Weksler, New York, N. Y., assignor to Weksler Thermometer Corporation, New York, N. Y., a corporation of New York

Application October 30, 1944, Serial No. 116,050

Term of patent 14 years

(Cl. D52—7)

To all whom it may concern:

Be it known that I, Harry Weksler, a citizen of the United States, residing at New York city, in the county of New York and State of New York, have invented a new, original, and ornamental Design for a Thermometer Case, of which the following is a specification, reference being had to the accompanying drawing, forming a part thereof.

Figure 1 is a front elevational view of a thermometer case embodying my new design;

Figure 2 is a rear elevational view;
Figure 3 is a side view;
Figure 4 is an end view;
Figure 5 is a longitudinal section taken along line 5—5 of Figure 1; and
Figure 6 is a transverse section taken along line 6—6 of Figure 1.

I claim:

The ornamental design for a thermometer case, as shown.

HARRY WEKSLER.
